HEZEKIAH S. BOWLER, OF GLOVERSVILLE, NEW YORK.

METHOD OF REMOVING AND REPLACING STORAGE-BATTERY CONNECTORS.

1,248,443.

Specification of Letters Patent. Patented Dec. 4, 1917.

Application filed May 3, 1917. Serial No. 166,201.

To all whom it may concern:

Be it known that I, HEZEKIAH S. BOWLER, a citizen of the United States, residing at Gloversville, in the county of Fulton and State of New York, have invented a new and useful Method of Removing and Replacing Storage-Battery Connectors, of which the following is a specification.

This invention has reference to a method of removing and replacing storage battery connectors, and its object is to avoid the necessity of skilled labor for such a purpose.

Ordinarily the lead terminal posts taper at their upper ends and the terminals have heads with reversely tapered passages therethrough to tightly fit on the tapered end of the post above which the connector extends and there forms a tapered pocket or receptacle into which lead is melted and caused to firmly unite with both the post and the connector by the process commonly known as burning. The process of lead burning is one requiring particular skill, and unless properly performed the junction is so poor that only imperfect electrical contact is obtained, with the result that the joint presents high electrical resistance, thereby materially cutting down the efficiency of the storage battery.

It becomes necessary from time to time to repair storage batteries, and in order to do this the connectors must be removed from the posts. The ordinary procedure is to bore out the burned in lead by means of a bit of suitable size until that portion of the post is reached which is not integrally joined with the connector, after which the connector is readily removed from the post. On replacing the connector and rejoining it to the post, it is needful to burn in a relatively large mass of lead, and the liability of imperfect junction is even greater than is the case when the connector is first joined to the post, since in boring out the filled in lead the boring must extend deeper than the original cavity in the head of the connector and a greater amount of lead is necessary than at first. Unless great care is taken, imperfect joints frequently occur and a repaired battery is often of less efficiency than a new battery from this one cause, since the resistance of the battery is increased at the connectors and the efficiency of the battery is correspondingly reduced.

Such troubles are entirely avoided and the reunion of the connector with the post may be accomplished even by unskilled labor, since there is no necessity of that degree of skill demanded in burning the lead connectors on to the posts in the usual way.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such changes and modifications come within the scope of the appended claims.

In the drawings:—

Figure 1 is a section through a storage battery electrode and its connector post showing a connector joined thereto in the usual manner.

Fig. 2 is a similar section but illustrating the initial step in the process of removing the connector from the post.

Fig. 3 is a similar section to Figs. 1 and 2 but showing the manner of completely loosening the connector from the post with a minimum disturbance of the uniting metal.

Fig. 4 is a view similar to the other views but showing the connector reunited to the post.

Referring to the drawings there is shown a storage battery electrode 1 with a terminal post 2, which latter, as is customary, has its free end 3 tapered. Applied to the post 2 is a connector 4 having a head 5 with a passage 6 therethrough having a tapered portion 7 fitting the tapered end 3 of the post, so as to provide a snug union, and above the post the passage 6 has a portion 8 tapering toward the post, thereby forming a widening pocket in a direction away from the post. When the connector is applied to the post and seated snugly thereon, a mass 9 of lead is melted into the pocket formed by the taper portion 8 of the passage 6, and by the process known as burning the lead is caused to intimately unite with the exposed end of the post and with the side walls of the part 8 of the opening 6, so that the union is to all intents and purposes

an integral union and ample electric contact is established, whereby the ohmic resistance of the joint between the connector and post is practically *nil*.

5 Should it become necessary to repair the battery, as frequently occurs, it is needful to remove the connector in order to have proper access to the electrode to make such repairs as should be made. Ordinarily, the
 10 filled in lead 9 is bored out to an extent about that of the diameter of the post 2, where it meets the smaller intermediate portion of the passage 6, so that the connector may be removed, since below such point the
 15 connector is only united to the post by contact and not by fusion. On replacing the connector it is necessary to fill in the bored out portion with lead fused therein by the burning process and as the mass of lead so
 20 placed is large, it requires the services of a skilled operator and even then there is a liability of imperfect union with consequent increase in resistance at the joint.

By this invention the removal of the connector from the post is not only facilitated, but the reunion of the connector with the post is made so simple as to be capable of performance by unskilled labor with a consequent reduction in cost.

25 30 The first step of the process is indicated in Fig. 2, where a hollow punch 10 is applied to the filler 9 and by striking such punch a suitable blow it is caused to sink a short distance into the filler 9 forming a groove 11 of
 35 a diameter corresponding to the width of the passage 6 where the two tapered portions 7 and 8 join. The groove 11 is utilized as a guide for a hollow reamer 12 by means of which an annular groove 13 is cut through
 40 the filler 9, and for a distance into the peripheral portion of the taper end 3 of the post to reach to that part of the post and connector where they are frictionally joined, but deeper than the fusion joint. This per-
 45 mits the ready removal of the connector the same as when the filler or plug 9 is bored out by a drill to a corresponding depth. When the connector is removed there remains a portion 9^a of the filler 9 as an integral part
 50 of the post 2 and rising above the taper end 3 of the post to the original height of the plug 9. There may also remain a portion 9^b of the filler 9 adherent to the inner wall of the head 5 of the connector where initially
 55 fused thereto.

When the connector is replaced after repairs have been made, it seats as originally upon the post 2, and the annular groove or kerf formed by the hollow reamer 12 may be
 60 then filled by fusing lead, indicated at 14, therein, after the manner of the burning process, such small amount of lead being readily fused into intimate union with the walls of the groove 13 and the stem and connector are as perfectly united as they were
 65

originally with the ohmic resistance between the connector and post reduced to practically zero.

By the customary procedure in removing and replacing connectors, the post is cut into 70 deeper and deeper on each removal of the connector, so that after two or three removals of the connector the post is so reduced in height as to necessitate the building up of the post in order to again receive the connector. 75

It is a material advantage of this invention that the height of the post is in no wise reduced by repeated removals of the connector and a post will outlast many removals 80 of the connector for repairs or other purposes.

The invention is therefore conducive to economy of repairs, since highly skilled labor is not needed and the connecting post 85 of the electrode has extremely long life, permitting repeated repairs to be made to the battery without material injury to the post, the height of the post remaining constant irrespective of the number of times the connector is removed and replaced. 90

What is claimed is:—

1. The method of removing connectors from the terminal posts of storage battery electrodes, which consists in cutting an annular groove through the metal uniting the connector and post, with the groove entering through the top of the connector and extended to a depth to be below the fused union between the connector and post. 95

2. The method of removing and replacing connectors from the terminal posts of storage battery electrodes, which consists in cutting an annular groove through the metal uniting the connector and post, with the groove entering through the top of the connector and extended to a depth to be below the fused union between the connector and post, and on replacing the connector after its removal from the post filling the groove 100 with lead and causing its integral union with the walls of the groove by burning. 105

3. The method of disconnecting integrally united connectors with the terminal posts of storage battery electrodes, which consists in 115 forming an annular preliminary guiding groove in the exposed face of the lead uniting the connector to the post, and then deepening the groove to a point where the connector and post are frictionally engaged, 120 thereby leaving a portion of the uniting metal on top of the post to the initial height and a portion of the uniting metal still integrally adherent to the connector. 125

4. The method of disconnecting and replacing integrally united connectors with the terminal posts of storage battery electrodes, which consists in forming an annular preliminary guiding groove in the exposed face of the lead uniting the connector to the 130

post, and then deepening the groove to a point where the connector and post are frictionally engaged, thereby leaving a portion of the uniting metal on top of the post to the initial height and a portion of the uniting metal still integrally adherent to the connector, and after the removal and replacing of the connector reuniting the connector to the post by filling in the groove with the lead 10 by burning to cause the lead so filled in to

integrally unite with those portions of the lead filling still carried by the post and by the connector.

In testimony, that I claim the foregoing as my own, I have hereto affixed my signature in the presence of two witnesses.

HEZEKIAH S. BOWLER.
